UNITED STATES PATENT OFFICE.

VERNEY A. WILSON, OF ATALLA, ALABAMA.

COMPRESSED-AIR ICE MACHINE.

Application filed November 23, 1920. Serial No. 426,028.

To all whom it may concern:

Be it known that I, VERNEY A. WILSON, a citizen of the United States, residing at Atalla, in the county of Etowah and State 5 of Alabama, have invented certain new and useful Improvements in a Compressed-Air Ice Machine; and I do hereby declare the following to be a full, clear, and exact description of the invention, such as will enable 10 others skilled in the art to which it appertains to make and use the same.

The object of the invention is to provide a simple and inexpensive apparatus for use in producing ice for commercial and like 15 purposes and which is adapted merely by modification as to proportions for domestic use; and with this object in view the invention consists in a construction and combination of parts of which a preferred 20 embodiment is shown in the drawing; wherein—

Figure 1 is a perspective view of an apparatus embodying the invention.

Figure 2 is a longitudinal sectional view 25 of the same.

Figure 3 is a transverse section on the plane indicated by the line 3—3 of Figure 2.

The device consists essentially of an ice 30 compartment or box 10 of any preferred or convenient proportions, completely housed within a casing 11 of which the walls are spaced from those of the ice compartment to form a fluid compartment 12 accessible 35 through an inlet 13, located in the construction illustrated at one end of the casing, for the refrigerating fluid such as compressed air which may be supplied from any suitable or convenient source (not shown) through 40 the supply pipe 14. The ice compartment is provided with a movable, preferably hinged, lid 15 which is normally closed to prevent the access of air but which may be displaced to permit of the introduction of water and 45 the removal of the ice, the walls and bottom of the compartment being provided with transverse grooves 16 for the reception of lifting rods 17 to facilitate the removal of the cake of ice from the compartment. 50 The lifting rods are of U-shape and snugly fit and fill the grooves 15 so as to avoid the formation of a recess or projection in the ice and the freezing of the rods in the ice. Said rods at their upper or free ends 55 are engageable by any suitable means to facilitate removal thereof and of the ice

therewith accordingly. At one end of the casing at the top there is provided an outlet door 18 which may be hinged as indicated at 19, to permit of the escape of the fluid contents of the compartment designed 60 for the refrigerant, but when in the preferred practice it is desired to graduate the exhaust of the refrigerating fluid it may be permitted to escape through a reduced outlet 19 provided with a valve 20. Latches 65 21 on door 18 engage keepers 22 on the cover of the casing. The fastening of door 18 thus locks lid 15 in place and the same securing means fastens both the door and lid in closed position. 70

In order to reinforce the construction to prevent the opening of the joints, the wall of the casing is preferably connected with the walls of the ice compartment by means of tie rods 21 consisting of bolts or the 75 equivalent thereof.

Having thus described the invention, what I claim is:—

1. A receptacle consisting of a casing; a box therein, a cover for the casing, a movable lid member on said cover for the box, a movable door member to permit access to the space intermediate the casing and the box, fastening means to secure one of said members in closed position, and said members having portions contacting with each other whereby said single fastening means will secure both of said members in closed position. 80 85

2. A receptacle consisting of a casing, a box therein spaced therefrom at the sides, end and bottom, bolts passing through the casing and threaded into said box, said bolts being disposed at different angles to support the box and casing out of contact to provide 90 a space therebetween, a cover for the casing, a movable lid member for the box on said cover, a movable door member to permit access to said space, said door member at one side thereof being engageable with the free end of the lid member, and a fastening means to secure said door member in closed position whereby the lid member is also secured in closed position through said engagement with the door member. 100 105

In testimony whereof I affix my signature in presence of two witnesses.

VERNEY A. WILSON.

Witnesses:

C. B. BORMAN,
W. A. MOORE.
